UNITED STATES PATENT OFFICE.

FRANCIS KARR, OF HOLLAND, MICHIGAN.

BED-SPRING.

1,205,900.

Specification of Letters Patent. Patented Nov. 21, 1916.

Application filed December 1, 1911, Serial No. 663,465. Renewed March 22, 1916. Serial No. 85,988.

To all whom it may concern:

Be it known that I, FRANCIS KARR, a citizen of the United States, residing at Holland, in the county of Ottawa and State 5 of Michigan, have invented certain new and useful Improvements in Bed-Springs, of which the following is a specification.

My invention relates to improvements in conical spiral spring bed mattresses, and 10 its objects are: First, to provide an absolutely flexible and pivotal connection between the surface coils of the springs. Second, to provide an absolutely flexible and pivotal connection between the surface coils 15 of the springs and at the same time extend material from which said connection is made across the surface coils to form an auxiliary support for the ticking of the bed that is supported by the springs; and, third, 20 to unite the connecting devices with the terminal ends of the spiral springs so firmly that no overlapping of the adjacent terminal coils will be possible, yet without impairment of the perfect flexibility of the 25 connecting elements between said coils. I attain these objects by the mechanism illustrated in the accompanying drawing, in which—

Figure 1 is a top plan of a set of six 30 springs to show one manner of interweaving the surface tie rods and inserting the pivotal springs. Fig. 2 shows a modified form for upper surface construction.

Similar letters refer to similar parts 35 throughout the several views.

In Fig. 1 I have shown the surface coils of the springs A as having slight lateral indentures or reverse curves at *a a*, which are designed as locking points where the pivotal springs B and the extended wire ends thereof, may be wound around, or tied to the surface coils in such a manner as to avert all danger of these ends slipping. In this instance the extended ends *b* are wound 40 around the coils A at the points adjacent to the springs B and at the points on the coils directly opposite to the springs B in such a manner as to form a supporting element across the top of the coils, as indicated. 45 The manner of winding extended ends around the coils is illustrated at *b'*.

In Fig. 2 I have shown modified forms of so securing the terminal ends of the helical springs to the terminal coils on the spiral

springs as to wholly avoid the danger of the 55 terminal ends moving or turning on the terminal coils and thus avoid producing a friction between the two that would weaken the connecting elements and produce unpleasant squeaking noises; thus, at *b'''* the 60 terminal end of the spring B is wound several times around the terminal coil A'' in such a manner as to render them non-turnable thereon, and at *b⁴* the terminal end, after having been wound around the terminal coil, A'' is passed diagonally across 65 said coil and secured to the opposite side thereof. By this construction, and also by the construction shown in Fig. 1 the danger of the coil turning loosely in the eyelet 70 formed in the wire *b* is wholly averted and all flexibility must be in the helical connecting springs B between the edges of the terminal coils of the spiral springs.

Another, and a very important object 75 attained by this construction as shown in both Figs. 1 and 2 is that a means is provided whereby the springs B are secured directly to the surface coils A or A'' of the bed springs thus averting the necessity, inconvenience 80 and expense of introducing a separate element to secure the flexible connecting springs B to the surface coils of the bed springs A or A'' independent of the surface coils, and at the same time I avoid the danger of drawing 85 the securing element off of the coils or off of the additional element that is introduced to secure the springs, also the danger of stretching and rendering the securing element inoperative.

What I claim as new, and desire to secure by Letters Patent of the United States, 90 is:

1. In spring bed bottom construction, surface coils having a series of lateral indentures, helical springs placed between the adjacent edges of the surface coils and securely connected directly with said coils and the integral ends of said springs passed across the surfaces of the coils and securely attached to 95 the opposite edges thereof at points of indention, substantially as shown.

2. In spring bed bottom construction, spiral springs having large terminal coils made serpentine in form by reason of oppositely disposed indentations, helical springs connecting said surface coils by means of tangential 100 ends of said springs wound around the wire 105

in the surface coils at given points and engaging two or more of the indentations in the surface coils in such a manner that the wire forming the surface coils cannot revolve in the windings of the tangential ends of the helical springs and cause grating and squeaking noises.

Signed at Grand Rapids Michigan November 29, 1911,

FRANCIS KARR.

In presence of—
I. J. CILLEY,
A. ALLGIER.
